UNITED STATES PATENT OFFICE.

THOMAS L. BURTON, OF ST. LOUIS, MISSOURI, ASSIGNOR TO AMERICAN BRAKE COMPANY, OF ST. LOUIS, MISSOURI, A CORPORATION OF MISSOURI.

BRAKE-HEAD CONNECTION.

1,199,869.

Specification of Letters Patent.

Patented Oct. 3, 1916.

Application filed February 20, 1915. Serial No. 9,563.

To all whom it may concern:

Be it known that I, THOMAS L. BURTON, a citizen of the United States, and a resident of St. Louis, in the State of Missouri, have invented a certain new and useful Improvement in Brake-Head Connections, of which improvement the following is a specification.

This invention relates to brake heads and hangers therefor, and has for its object to provide improved connecting means whereby the brake head and shoe will be automatically adjusted upon its pivot, by engagement with the car wheel, to such position that the shoe is concentric with the wheel, and then be retained in the same position relative to the hanger until again shifted by engagement with the wheel.

In the accompanying drawings: Figure 1 is a side elevation of a brake head and hanger showing one form of connection embodying my improvement; Fig. 2, a transverse section of the same; Fig. 3, a similar transverse section showing a slight modification; Fig. 4, a side elevation showing another modification; Fig. 5, a transverse section of the same; Figs. 6 to 15, similar sections showing other modifications; Figs. 16 and 17, a side elevation and transverse section, respectively, showing another modification; and Figs. 18 to 23, similar views, showing still further modifications.

It is important in the operation of railway brakes that the brake heads be supported in such a manner that when the brakes are released all parts of the rubbing surfaces of the shoes are effectually prevented from coming into contact with the wheels, otherwise undesirable wear and loss of power would be occasioned. At the same time it is equally important that when the brakes are applied the shoes be permitted to so adjust themselves relatively to the wheels that the rubbing surfaces of the shoes become concentric with the wheels, thus providing for substantially uniform pressure and wear on all parts of the rubbing surfaces of the shoes.

According to the construction shown in Figs. 1 and 2 of the drawings, the brake

head, 1, carrying the shoe, 2, is pivotally mounted on the hanger, 3, by means of a pin, 4, passing through the hanger and the two flanges of the brake head. According to my improvement, one of the supporting flanges of the brake head is provided with an opening in which is mounted a longitudinally movable bushing, 5, on the connecting pin, 4, while a spring and clamping nut on the pin serve to exert a pressure and produce a corresponding frictional resistance between said bushing and the hanger, and between the hanger and one of the brake head flanges. As shown in Figs. 1 and 2, the movable bushing, 5, is of hexagonal or other non-circular form, and contains a recess for the head of the pin or bolt, 4, so that the bushing and bolt turn with the brake head.

The hanger, 3, is provided with friction surfaces upon its opposite sides around the bolt opening for engaging a corresponding surface on the bushing on one side and on the other brake head flange on the other side, these parts being pressed against each other by the spring, 6, which is mounted on the bolt outside of one of the brake head flanges, and bears at its outer end against the washer, 7, held by the nut, 8, on the bolt. The force of the spring holds the friction faces in contact with sufficient pressure to maintain the same relative position between the brake shoe and hanger when the brake is released as when applied to the wheel. In this way all parts of the rubbing surface of the shoe are effectually prevented from coming into contact with the wheel when the brake is released, and at the same time the shoe is permitted to readily so adjust itself relatively to the wheel that the rubbing surface of the shoe becomes concentric with the wheel when the brake is applied, for as soon as any wear or other cause tends to disturb this relation the application of the shoe to the wheel will force the head to turn slightly on its pivot pin on the hanger and sufficiently to reestablish the concentric relation above referred to. The frictional engagement between the surfaces of the brake head and the movable

bushing and the corresponding surfaces on the hanger will then hold the parts in this position until further adjustment is made.

The spring, 6, may be an ordinary helical spring of round section or a short coil of square section, as shown in Fig. 3.

According to the modification shown in Figs. 4 and 5, the longitudinally movable bushing, 5^a, is cylindrical and is mounted 10 in the flange of the head on the same side as the spring. In this case, the bushing may turn with the hanger and relatively to the brake head unless the torsional resistance of the spring, 6, is exceeded, in which event 15 relative motion will occur between the bushing and the hanger, or between the bushing and the spring, or between the spring and the washer, 7, or between the washer and the nut, 8, which is constrained to turn with 20 the brake head. In any case there is the frictional resistance to the motion of the hanger relatively to the brake head of the engaging surfaces of the hanger and the brake head flange on the other side, which is 25 ample for the purpose intended. Fig. 6 shows the use of the short coil square section spring in connection with the cylindrical bushing.

In the modification shown in Fig. 7, a 30 short coil of square section spring, 5^b, serves both as the longitudinal movable bushing and as the spring, and bears directly upon the friction face at one side of the hanger, passing through the enlarged cylindrical opening in the flange of the brake head.

According to Fig. 8, the spring, 6, is dispensed with, and in lieu thereof, a spring washer, 9, is used under the head of the bolt, 4.

40 In the modification shown in Fig. 9, the construction is the same as that of Fig. 7, with the addition of the use of the spring washer, 9, beneath the bolt head.

In Figs. 4 to 9 inclusive, it is apparent 45 that the frictional engagement with the left side of the hanger is not a positive one, for if the head is rotated relatively to the hanger, the bushing, 5^a, or its equivalent, 5^b, will rotate with the hanger, coiling or un- 50 coiling the spring about its central axis until the torsional resistance of the spring becomes sufficient to prevent its further distortion; then when the force which occasioned the rotation of the head ceases to be 55 exerted on it, the tendency of the spring to recoil will continue to cause a force to act on the head tending to restore the head to its original position relative to the hanger.

In order to maintain the same relative 60 position between the brake head and hanger when the brake is released as when applied, it is important that the frictional engagements on which the maintenance of this relation depends be positive in their action and

free at all times from any tendency to cause 65 rotation of the head relatively to the hanger.

In Fig. 10 it will be noted that the construction is similar to that of Figs. 4 and 5, with the exception that the bushing, 5^a, is prevented from rotating relatively to the 70 brake head by means of the key, 10, and the bolt, 4, the head of which is lodged in a recess in one of the side flanges. In Fig. 11 the bushing, 5^a, is prevented from rotating relatively to the brake head by means of the 75 key, 10^a, engaging with the left-hand side flange. It will be observed that in both of these figures means are provided for forming two frictional engagements with the surfaces of the hanger, each of which is adapted to uniformly oppose the rotation of the 80 brake head relatively to the hanger.

The constructions shown in Figs. 12 and 13 are substantially the same as those of Figs. 1, 2 and 3 with the exception that instead of the bushing, 5, the bolt itself is adapted to form a bearing for the brake head flange and also to have frictional engagement with the face of the hanger. In Fig. 12 the bolt is provided with an enlargement or collar, 4^a, and in Fig. 13 the head of the bolt itself is extended to perform the functions in question. In both cases the bolt is prevented from rotating relatively to the brake head by means of a hexagonal recess in the side flange which engages the bolt head.

In Fig. 14, a bushing, 5^a, rotatable relatively to the brake head is mounted on the bolt, 4, within the left side flange. The bolt, 100 4, is non-rotatably connected with the hanger by means of the key, 12, and the head of the bolt is adapted to have frictional engagement with the outer surface of the right-hand side flange. The object of this 105 construction is to provide frictional engagements with the inner and outer surfaces of one of the side flanges.

In Fig. 15, the bushing, 5, which is rotatable relatively to the brake head is mounted 110 on the bolt, 4, within one of the side flanges; also a washer, 11, is mounted on the bolt, 4, outside of the other side flange and is prevented from rotating relatively to the bolt by means of the key, 10. A key, 12, connects the bolt, 4, with the hanger, 3, so that these parts cannot rotate relatively to each other. It is apparent that the spring, 6, presses the washer, 11, and the hanger, 3, into frictional engagement with the opposite faces of one of the side flanges, also that both of these engagements are of a positive character for when the hanger is rotated relatively to the brake head, the bolt, 4, and washer, 11, must turn with it. It will be 115 obvious that, if preferred, the bushing may be integral with the bolt.

In the constructions shown in Figs. 1 to 15

inclusive, no rotation whatever of the brake head relative to the hanger can occur without considerable frictional resistance, and such a condition not only fulfills all requirements but also is subject to no objections when the upper end of the hanger is pivoted to some part of the truck, as for example an equalizing bar, which is not spring supported, for in such instances there can be no relative motion between the wheel and the head while the brake is applied, and, therefore, no unnecessary wear of the friction surfaces will be occasioned. However, when, as is frequently the case, the hanger is pivoted to some spring-supported part of the truck, the head will move almost constantly, though slightly, relatively to the wheel during a brake application because of the more or less uneven nature of all road beds, with the result that the head will then be forced to rotate through a small angle relatively to the hanger. Consequently in order to permit this slight rotation without any attendant wear of the friction surfaces, the modified construction shown in Figs. 16 to 23 have been devised.

As shown in Figs. 16 and 17, bushings, 5 and 5^a, are mounted on the bolt, 4, on opposite sides of the hanger, 3, and the bushing, 5^a, is rotatable relatively to the brake head. The bushing, 5, is provided with a lug, 13, which is adapted to engage with the stops, 1^a and 1^b, cast integral with the right hand side flange of the brake head. As clearly indicated in Fig. 16, these stops are so arranged that the space between same is slightly greater than the width of the lug, 13. Consequently when the hanger rotates relatively to the brake head through the small angle no frictional resistance to such rotation is encountered until the lug, 13, engages either one or other of the stops, 1^a or 1^b. The bushing, 5, may be formed integral with the bolt, if desired.

The construction shown in Figs. 18 and 19, includes a washer, 11, mounted on the bolt, 4, and non-rotatively connected therewith by the key, 10, the washer, 11, having frictional engagement with the outer surface of the left-hand side flange. The bolt, 4, is connected with the hanger, 3, by means of a key, 12, which is driven tightly into the key-way in the hanger. The head of the bolt, 4, is adapted to have frictional engagement with the outside surface of the right-hand side flange. The key-way in the bolt engaging the key, 12, may be wider than the key as indicated in Fig. 19 so as to permit the hanger to rotate through a restricted angle without having to carry the bolt with it, or the key-way in the bolt may closely fit the key, 12, so as to make the hanger non-rotatable relatively to the bolt. Obviously both of these constructions embody two posi-

tive frictional engagements with the surfaces of the side flanges, the same being adapted to uniformly oppose the rotation of the brake head relatively to the hanger. 65

In the construction shown in Figs. 20 and 21, bushings, 5 and 5^a, are mounted on the bolt, 4, on opposite sides of the hanger, 3, with which they have frictional engagement. Keys, 10^a, are fitted into these bushings and are adapted to either limit or prevent the rotation of the same relatively to the brake head flanges as indicated in Fig. 21. If the bolt is rotatable relative to the hanger there will be two frictional engagements with the surfaces of the hanger. If the bolt is keyed, or otherwise fastened to the hanger, two additional frictional engagements will be provided for, namely, the positive engagement of the bolt head with the bushing, 5, and the variable one between the bushing, 5^a, and the spring, 6. 70 75 80 85

The construction shown in Fig. 22 is similar to that of Figs. 16 and 17. The hanger, 3, is non-rotatably connected to the bolt, 4, by the key, 12. The bushings, 5 and 5^a, are provided with lugs, 13 and 13^a, adapted to engage stops, 1^a and 1^b, cast integral with the brake head flanges and so located as to permit the bushings to rotate slightly relatively to the brake head. This construction provides for three positive and one variable frictional engagements opposing the rotation of the head relative to the hanger. 90 95

The construction shown in Fig. 23 includes bushings, 5 and 5^a, mounted on the bolt, 4, on opposite sides of the hanger, 3, and a washer, 11, also mounted on the bolt, 4, outside of the left-hand bushing with which it has frictional engagement. A key, 10, prevents the washer, 11, from rotating relatively to the bolt. A key, 12, prevents the hanger, 3, from rotating relatively to the bolt, and keys, 10^a, either limit or prevent the rotation of the bushings, 5 and 5^a, relatively to the brake head flanges. This construction clearly embodies four positive frictional engagements, 100 105 110 each of which is adapted to uniformly oppose the rotation of the brake head relatively to the hanger.

It will be obvious that the surfaces for frictional engagement may be of any desired character and form, and that any suitable means other than keys may be employed for preventing relative rotation between the parts. 115

Having now described my invention, what I claim as new and desire to secure by Letters Patent is:

1. The combination of a brake head having side flanges, a hanger between said flanges and rotatable relatively thereto, means for forming a plurality of enforced frictional engagements adapted to uniformly oppose the rotation of the brake 120 125

- head relatively to the hanger, and means for limiting the magnitude of the opposing forces developed by said enforced frictional engagements.
5. 2. The combination of a brake head having side flanges, a hanger between said flanges, a bolt passing through the same, and means mounted on said bolt, and connected with the brake head, for forming frictional engagement with the hanger.
10. 3. The combination of a brake head having side flanges, a hanger between said flanges, a bolt passing through the same, and means mounted on said bolt, and so connected with the brake head as to be rotatable relatively thereto within restricted limits, for forming frictional engagement with the hanger.
15. 4. The combination of a brake head having side flanges, a hanger between said flanges, a bolt passing through the same, and means mounted on said bolt, and non-rotatably connected thereby with said hanger, for forming frictional engagement with the brake head.
20. 5. The combination of a brake head having side flanges, a hanger between said flanges, a bolt passing through the same, and means mounted on said bolt, and so connected with the hanger as to be rotatable relatively thereto within restricted limits, for forming frictional engagement with the brake head.
25. 6. The combination of a brake head having side flanges, a hanger between said flanges, a bolt passing through the same, and means mounted on said bolt, and so connected thereby with the hanger as to be rotatable relatively thereto within restricted limits, for forming frictional engagement with the brake head.
30. 7. The combination of a brake head having side flanges, a hanger between said flanges, a bolt passing through the same, and a bushing mounted on said bolt within one of the side flanges of the head and having a frictional engagement with the hanger.
35. 8. The combination of a brake head having side flanges, a hanger between said flanges, a bolt passing through the same, a bushing mounted on said bolt within the opening in one of the side flanges, and means for pressing the bushing into frictional engagement with the hanger.
40. 9. The combination of a brake head having side flanges, a hanger between said flanges, a bolt passing through the same, a bushing mounted on said bolt within the opening in one of the side flanges, and a spring mounted on said bolt outside of said flanges for forcing the bushing into frictional engagement with the hanger.
45. 10. The combination of a brake head having side flanges, a hanger between said flanges, a bolt passing through the same, and means mounted on said bolt within the opening in one of the side flanges, and having a longitudinally movable bushing mounted on said bolt within one of the side flanges of the head, and having a frictional engagement with the hanger.
50. 11. The combination of a brake head having side flanges, a hanger between said flanges, a bolt passing through the same, a longitudinally movable bushing mounted on said bolt within the opening of one of the side flanges, and means for pressing the bushing into frictional engagement with the hanger.
55. 12. The combination of a brake head having side flanges, a hanger between said flanges, a bolt passing through the same, a longitudinally movable bushing mounted on said bolt within the opening in one of the side flanges, and a spring mounted on said bolt outside of said flanges for forcing the bushing into frictional engagement with the hanger.
60. 13. The combination of a brake head having side flanges, a hanger between said flanges, a bolt passing through the same, a bushing mounted on said bolt within the opening in one of the side flanges, and having a frictional engagement with the hanger, and means for preventing a material rotation of the bushing relatively to the brake head.
65. 14. The combination of a brake head having side flanges, a hanger between said flanges, a bolt passing through the same, bushings mounted on said bolt within the side flanges, and having frictional engagement with the hanger, and means for restricting the rotation of said bushings relatively to the brake head within specific limits.
70. 15. The combination of a brake head having side flanges, a hanger between said flanges, a bolt passing through the same, bushings mounted on said bolt within the side flanges, means for restricting the rotation of said bushings relatively to the brake head within specific limits, and means for forcing the bushings into frictional engagement with the hanger.
75. 16. The combination of a brake head having side flanges, a hanger between said flanges, a bolt passing through the same, a bushing on said bolt within one of the side flanges and forming a frictional engagement with the hanger, a longitudinally movable bushing mounted on said bolt within the other side flange, and having frictional engagement with the hanger, and means for restricting the rotation of said bolt relatively to the brake head within specific limits.
80. 17. The combination of a brake head having side flanges, a hanger between said flanges; a bolt passing through the same, a

bushing on said bolt within one of the side flanges, a longitudinally movable bushing mounted on said bolt within the other side flange, means for restricting the rotation of 5 said bolt relatively to the brake head within specific limits, and means for forcing said bushings into frictional engagement with the hanger.

18. The combination of a brake head having side flanges, a hanger between said flanges, a bolt passing through the same, an enlarged portion on said bolt on one side of the brake head having frictional engagement, a slideable and non-rotatable washer mounted on the bolt on the opposite side of the brake head, and having frictional engagement with the other side flange, and means for preventing said bolt from rotating relatively to the hanger.

19. The combination of a brake head having side flanges, a hanger between said flanges, a bolt passing through the same, bushings mounted on said bolt within the side flanges on opposite sides of the hanger, 25 and having frictional engagement therewith, means for preventing a material rotation between said bushings and the brake head flanges, and means from preventing the bolt from rotating relatively to the 30 hanger.

20. The combination of a brake head having side flanges, a hanger between said flanges, a bolt passing through the same, bushings mounted on said bolt within the 35 side flanges on opposite sides of the hanger, means for preventing a material rotation between said bushings and the brake head flanges, means for preventing the bolt from rotating relatively to the hanger, and means 40 for forcing the bushings into frictional engagement with the hanger.

21. The combination of a brake head having side flanges, a hanger between said flanges, a bolt passing through the same, 45 bushings mounted on said bolt within the side flanges on opposite sides of the hanger, and having frictional engagement therewith, means for restricting the rotation of 50 said bushings relatively to the brake head flanges within specific limits, and means for preventing the bolt from rotating relatively to the hanger.

22. The combination of a brake head having side flanges, a hanger between said flanges, a bolt passing through the same, bushings mounted on said bolt within the side flanges on opposite sides of the hanger, 55 means for restricting the rotation of said bushings relatively to the brake head flanges within specific limits, means for preventing the bolt from rotating relatively to the hanger, and means for forcing the bushings into frictional engagement with the hanger.

23. The combination of a brake head hav-

ing side flanges, a hanger between said flanges, a bolt passing through the same, bushings mounted on said bolt within the side flanges on opposite sides of the hanger, and having frictional engagement therewith, means for preventing a material rotation between said bushings and the brake head flanges, means for preventing the bolt from rotating relatively to the hanger, an enlarged portion on said bolt having frictional engagement with one of the bushings on one side of the brake head, and a slideable and non-rotatable washer mounted on the bolt on the opposite side of the brake head, and having frictional engagement with the other of said bushings.

24. The combination of a brake head having side flanges, a hanger between said flanges, a bolt passing through the same, bushings mounted on said bolt within the side flanges on opposite sides of the hanger, 85 means for preventing a material rotation between said bushings and the brake head flanges, means for preventing the bolt from rotating relatively to the hanger, an enlarged portion on said bolt on one side of the brake head, a slideable and non-rotatable washer mounted on the bolt on the opposite side of the brake head, and means for forcing the bushings into frictional engagement with the hanger, with said washer, and with 90 the enlarged portion of the bolt.

25. The combination of a brake head having side flanges, a hanger between said flanges, a bolt passing through the same, bushings mounted on said bolt within the 100 side flanges on opposite sides of the hanger, and having frictional engagement therewith, means for restricting the rotation of said bushings relatively to the brake head flanges within specific limits, means for preventing the bolt from rotating relatively to the hanger, an enlarged portion on said bolt having frictional engagement with one of the bushings on one side of the brake head, and a slideable and non-rotatable washer 110 mounted on the bolt on the opposite side of the brake head, and having frictional engagement with the other of said bushings.

26. The combination of a brake head having side flanges, a hanger between said flanges, a bolt passing through the same, bushings mounted on said bolt within the side flanges on opposite sides of the hanger, 115 means for restricting the rotation of said bushings relatively to the brake head flanges within specific limits, means for preventing the bolt from rotating relatively to the hanger, an enlarged portion on said bolt on one side of the brake head, a slideable and non-rotatable washer mounted on the bolt 120 on the opposite side of the brake head, and means for forcing the bushings into frictional engagement with the hanger, with 125

said washer, and with the enlarged portion of the bolt.

27. The combination of a brake head having side flanges, a hanger between said flanges rotatable relatively thereto, means for forming frictional engagements adapted to oppose the rotation of the brake head relatively to the hanger, and means for per-

mitting the brake head to rotate through a restricted angle without opposition from 10 said frictional engagements.
